UNITED STATES PATENT OFFICE.

WILLIAM GUILLIAUME, OF MILWAUKEE, WISCONSIN, ASSIGNOR TO GENERAL INDUSTRIAL X-RAY CO., OF MILWAUKEE, WISCONSIN, A CORPORATION OF WISCONSIN.

DESIGN FOR A CABINET.

Application filed January 3, 1922. Serial No. 4. Term of patent 3½ years.

To all whom it may concern:

Be it known that I, WILLIAM GUILLIAUME, a citizen of the United States, residing at Milwaukee, in the county of Milwaukee and State of Wisconsin, have invented a new, original, and ornamental Design for a Cabinet, of which the following is a specification, reference being had to the accompanying drawing, forming part thereof.

The single figure is a perspective view of my new and ornamental design.

I claim:

The ornamental design for a cabinet, as shown.

In testimony that I claim the foregoing I have hereunto set my hand at Milwaukee, in the county of Milwaukee and State of Wisconsin.

WILLIAM GUILLIAUME.
